UNITED STATES PATENT OFFICE.

EDWIN T. GREENFIELD, OF KIAMESHA, NEW YORK.

ART OF TREATING TUBES INTERIORLY WITH LIQUID COATING AGENTS.

1,146,791.

Specification of Letters Patent. Patented July 20, 1915.

Application filed January 23, 1912, Serial No. 672,826. Renewed December 15, 1914. Serial No. 877,446.

To all whom it may concern:

Be it known that I, EDWIN T. GREENFIELD, a citizen of the United States, and resident of Kiamesha, county of Sullivan, and State of New York, have made a new and useful Invention in the Art of Treating Tubes Interiorly with Liquid Coating Agents, of which the following is a specification.

My invention is directed particularly to a novel method of and also to a novel mechanism for effecting such coating and it has for its objects—First, to effect great speed in the coating of such tubes. Second, to effect a better interior coating than has heretofore been effected, by reason of the peculiar action of the apparatus. Third, to effect such coating with a minimum waste of material and with the best possible disposition of the same.

20 My invention will be fully understood by referring to the accompanying drawings, in which,

Figures 1 and 2, when placed end to end with Fig. 1 on the left, are longitudinal sectional views of the entire apparatus, part of the mechanism being shown in side elevation. Fig. 3 is an enlarged sectional view taken on the broken line X—X Fig. 1, and as seen looking thereat from right to left in the direction of the arrows.

Referring now to the drawings in detail, 1 1 represent the floor of the room where the apparatus is to be used and 2, 2, are legs supporting the frame 3 of the machine.

35 4, 4, are grooved guide-ways for sustaining the tube to be treated, said guide-ways being supported and secured directly by the frame.

5 represents a tube in position as it is being treated.

6 represents a bracket secured by bolts to the legs 2, its function being to support the liquid treating material, preferably black shellac in solution with alcohol, in a tank or 45 chamber 7 provided with a cover and a partition near one end to prevent evaporation, said partition being open at the bottom.

8 represents an air pipe running in the direction of the arrows from a source of compressed air and secured directly to the frame 3.

50 9 represents a cock for cutting off the air supply and 10 an additional cock located near the operator for effecting the operation in each pipe, there being one of these cocks 10 in each of the branch air pipes and only one

cock 9 which regulates the entire air supply. The pipe 8 is connected at its left hand end to a number of smaller pipes 11.

12 are additional pipes running therefrom and from the same source of air supply to air tight cylinders, and 13 are vertically movable pipes extending from the bottoms of said air tight cylinders to liquid carrying cups 14 which are supported by side rods 15 60 15 and are connected at their tops to a piston rod 16, all of these parts being supported or sustained by a bracket 17 on an upright 24 of the frame.

18 are cylinders and 19 are supports or 70 standards (see Fig. 1) for air chambers 21.

20 are pistons located in the cylinders 18 and designed to lift the cups 14 so as to place the ends of the pipes 13 in the coating liquid, as will be described later on.

75 22 are air pipes running from the air chambers 21, each of their free ends being provided with a screw-threaded connector 23 of the desired diameter to attach thereto the screw-threaded end of the tube 5 80 which is to be treated.

26 is an adjustable stop for the upper ends of the piston rod 16 and is connected to the upright 24 by an adjustable bolt 27 having play or movement in an oblong slot 28.

85 29 (see Fig. 2) is a vessel for receiving the surplus coating material after it is blown through the tube which is being treated, said vessel being sustained upon the floor 1 by four legs 30, 30.

90 31 is the mouth of the vessel 29.

32 is the cover of the vessel and 33 represents a portable vessel for receiving the coating material when it is withdrawn from the vessel 29.

95 34 is an outlet pipe, 35 being a cock adapted to release the material and allow it to run into the portable vessel 33.

I have shown in Figs. 1 and 2 of the drawings an apparatus for treating two tubes 100 at the same time; of course, it will be understood that any number of tubes may be treated this way by merely duplicating the parts.

The operation is as follows—The tank or 105 chamber 7 is filled to the proper depth with the necessary liquid material with which it is designed to treat tubes, preferably any liquid paint of the desired consistency, and air is admitted to the pipe 8 under pressure 110 but is prevented from passing outward by the stop cocks 9 and 10. The attendant se-

cures the tube 5 to be treated to the screw-threaded connector 23. The cocks are then opened and air permitted to pass in the direction of the arrows. When it reaches the 5 extreme left hand end of the machine it passes by branches 11, 11, to two sets of duplex treating apparatus, as shown in Fig. 3; first by way of the chamber 21 to the pipe 22, a second branch 12 passing directly 10 to the lower end of the cylinder 18 beneath the piston 20, thereby causing it—the piston—to be raised and hence imparting upward motion to the piston rod 16 and the two side rods 15 which carry the cup 14. 15 When these side rods assume the extreme upper limit they come in contact with the adjustable stop 26, but before this has been accomplished the pipe 13 enters the cup 14 a definite distance, dependent upon the adjustment of the stop 26 and permits the coating material to be subjected to the vacuum produced in the pipe 13 by the inflow of air through the pipe 22 and the tube 5 which is being treated. This continues until 20 the desired amount of coating material, dependent upon the depth of the pipe 13 in the cup 14 and the adjustment of the stop 26, has been exhausted. The attendant sees when this occurs by observing the open end 25 of the tube 5, noticing when the discharge of vapor discontinues. He immediately closes the cock 10 when the machine ceases operation and the cup 14 again descends to its lowest point in the vessel, as shown in 30 Fig. 1. The tube 5 which has been fully treated is then disconnected from the connector 23 and the apparatus is ready for treatment of another tube. In the same manner an attendant may attend to the 35 treatment of two tubes upon a parallel pipe 22 as seen on the right in Fig. 3, the operation of these pistons 20 for the cylinders 18 being exactly alike in their action. In this way one attendant may readily attend 40 to the treatment of two tubes at one time and the apparatus will effect the coating of the interior of the tubes with a liquid bath to the desired extent, dependent upon the adjustment of the machine. 45 It will be noted that the compressed air acting upon the interior of the tube, after having supplied the necessary amount of material, effectually spreads the same throughout the surface and ultimately forces 50 out the surplus material into the vessel 29, from which it may be drawn off into the portable vessel 33 and again placed in the tank 7 and used as before. 55 By means of different sized connectors 23 and the variable adjustment of the stop 26 I am enabled to treat tubes of variable size. Variations in the effect of the coating may also be produced by varying the pressure at the source of air supply, in accordance with 60 the pressure it is desired to exert, so that

an air pressure gage will give to the attendant an indication to this effect, it being understood that with paints or substances of different consistencies the pressure may be varied to suit the same and by such adjustment I am enabled to coat the tube to the most exact nicety, never leaving any surplus material within the same. 70

I do not limit myself to the special structural arrangement shown, as it is obvious 75 that my novel method of treatment may be effected by various kinds of apparatus.

I believe it is broadly new with me to coat the interior surface of the tubes with a liquid paint by compressed air and to apply it in such manner that only the necessary amount for producing the desired result is required, and this I accomplish by a variation of the supply in the manner described and also by varying the pressure of 80 the air acting to distribute this coating material in the manner described. 85

Having thus described my invention what I claim and desire to secure by Letters Patent of the United States is— 90

1. The herein described method of treating a tube interiorly with a liquid coating agent, which consists in directing by a suitable blast a spray of the liquid agent axially through a tube, and directing then, the same 95 blast axially through the tube to spread such sprayed liquid agent on the interior of the latter and remove any excess.

2. The herein described method of treating a tube interiorly with a liquid coating 100 agent, which consists in spraying by a suitable blast an excess of the liquid agent axially through a tube, and directing then, the same blast axially through the tube to spread such sprayed liquid agent on the interior of the latter and remove the said 105 excess.

3. The herein described method of treating a tube interiorly with a liquid coating agent, which consists in spraying by a suitable blast an excess of the liquid agent axially through a tube, directing then, the same blast axially through the tube to spread such sprayed liquid agent on the interior of the tube and remove the surplus 110 and discharging the surplus liquid agent from the latter. 115

4. The herein described method of treating a tube interiorly with a liquid coating agent, which consists in supporting a tube 120 with one end open to the atmosphere, spraying by a suitable blast an excess of the liquid agent axially through the tube, and directing then, the same blast axially through the tube to spread such sprayed liquid agent on the interior of the tube and blow off any excess and discharging the surplus liquid agent from the open end of the latter. 125

5. The herein described method of treating a tube interiorly with a liquid coating 130

- agent, which consists in subjecting a pre-determined supply of the liquid agent to the injector action of a suitable blast for vaporizing such liquid agent and entraining the 5 vapor in such blast, directing such blast and entrained vapor axially through a tube, and directing then, the same blast axially through the tube to spread such liquid agent on the interior of the latter.
- 10 6. A machine for coating tubes interiorly with a liquid coating agent, embracing an atomizing device for spraying a liquid agent axially through a tube, a receptacle shiftable relative to said atomizing device for 15 supplying a liquid agent to the latter, means for automatically shifting said receptacle to operative position, and adjustable means for regulating the shifted position of said receptacle.
- 20 7. A machine for coating tubes interiorly with a liquid coating agent, embracing an atomizing device for spraying a liquid agent axially through a tube, a receptacle shiftable relative to said atomizing device for 25 supplying a liquid agent to the latter, means for supplying compressed air to said atomizing device, and pneumatic means actuated by such compressed air supply for automatically shifting said receptacle to operative 30 position.
8. The herein described method of treating an open-ended tube with a liquid coating agent, which consists in fitting tight into one end of said tube, a blast nozzle, while 35 supporting the tube, with its other end open,
- supplying the coating material in quantity proportioned to the size of the tube, in one charge, to the said nozzle, directing the blast and the material carried thereby axially through the tube, to spread such liquid agent 40 upon the interior face of the tube, and continuing the blast after the liquid charge is used up, to remove any surplus liquid.
9. The herein described method of coating the interior of open-ended tubes, which 45 consists in fitting tight one end of such a tube against a blast discharge, supplying, under control of the blast, to the blast, liquid coating in quantity adapted to each tube, directing the blast and coating lengthwise of the tube, until the coating charge is used up, and continuing the blast to remove any surplus.
10. A machine for coating the insides of open-ended tubes, consisting of a spraying 55 device adapted to be fitted to the end of a tube and discharging along the axis of said tube, means for supplying charges of liquid coating to the spray, said supply means, being arranged to be controlled by the spray 60 blast, to supply a quantity adapted to each tube.

In testimony whereof I have signed my name to this specification in the presence of two subscribing witnesses.
